UNITED STATES PATENT OFFICE.

WILHELM KNIPPENBERG, OF DUSSELDORF, GERMANY.

HAIR-CURLER.

1,161,053.

Specification of Letters Patent. Patented Nov. 23, 1915.

Application filed September 29, 1913. Serial No. 792,369.

To all whom it may concern:

Be it known that I, WILHELM KNIPPENBERG, a subject of the King of Prussia, German Emperor, residing at Dusseldorf, in the Kingdom of Prussia, German Empire, have invented certain new and useful Improvements in Hair-Curlers, of which the following is a specification.

This invention relates to hair curlers of 10 that type in which the tube around which the hair is wound is mounted in a pivotable U-shaped holder and in which a heated rod is inserted in the tube for heating the hair. With hair curlers of this type it happens 15 sometimes that the hair is singed as the heat is directly transmitted to the tube around which the hair is wound. A further inconvenience connected with such hair curlers is that the heating rod easily drops out of the 20 curling tube.

The invention has for its purpose to avoid these inconveniences by improving the construction of the hair curlers of that type.

In the accompanying drawings the invention is shown by way of example.

Figure 1 is a front elevation of the improved hair curler; Fig. 2 is a plan view of Fig. 1 the handle being removed; Fig. 3 is a vertical longitudinal section of Fig. 1; 30 Figs. 4 and 5 show the hair curler in front view and in side elevation respectively, certain parts being represented in section; Fig. 6 shows, on a larger scale partly in elevation and partly in section, the upper end of 35 the curling sleeve and heating rod.

The improved hair curler essentially consists of a curling tube *a* having an inwardly turned flange *a'* at the upper end and two longitudinal slots *b* and *b'* near the lower 40 end, of the U-shaped holder *c* the upper ends of whose arms are connected by a cross piece *d* which also maintains the curling tube, of a spiral spring *e* located in the curling tube and bearing with one end 45 against the inwardly turned flange *a'* of said curling tube and with the other end against the middle part of said U-shaped holder *c*, and of the heating rod *f*. The heating rod *f*, which is made from metal, has a handle *f'* 50 of insulating material, preferably wood. The upper threaded end *g* of the heating rod *f* is screwed into the wooden handle and projects from the same so that it can be 55 screwed into the threaded flanged end *a'* of the curling tube.

The improved hair-curler is used as follows:—The curling tube *a* is pulled in the direction of the arrow (Fig. 4) so that its upper end gets out of the eye of the cross piece *d* of the holder, the spiral spring being compressed. The curling tube is turned in the direction of the arrow (Fig. 5) so that it gets out of the U-shaped holder *c*. After the hair has been wound around the curling tube *a* this tube is brought back to 60 the normal position in which it is maintained by the action of the spiral spring *e*. The heating rod *f* is inserted through the eye of the cross piece *d* of the holder into the upper end of the curling tube so that it 65 is located in the spiral spring *e* which prevents it from coming in contact with the wall of the curling tube. The upper end of the heating rod is screwed into the threaded flange *a'* so that it cannot drop out of the 70 tube (Fig. 6).

It is not necessary that the spiral spring extends over the entire length of the curling tube as it merely serves, on the one hand to maintain the curling tube in the 75 normal position and, on the other hand to prevent the heating rod coming in contact with the wall of the curling tube.

I claim:—

An improved hair curler comprising in 80 combination a curling tube, an inwardly turned internally threaded flange at the outer end of said curling tube, a U-shaped holder mounted in said curling tube, a cross piece with an eye at the middle fixed upon 85 the ends of the U-shaped holder said eye being designed to receive the outer end of the curling tube, a spiral spring located in said curling tube for maintaining the same in its position with its outer end in said eye 90 holder, a heating rod to be inserted into said spiral spring for heating the curling tube, an upper threaded end of said heating rod adapted to be screwed into the threaded flange of the curling tube, and a handle 95 of insulating material on said upper threaded end of the heating rod, substantially as described and shown and for the purpose set forth.

In witness whereof I have hereunto set 100 my hand in the presence of two witnesses.

WILLY KNIPPENBERG. [I. S.]
